UNITED STATES PATENT OFFICE.

JOSEPH E. PERRAULT, OF WATERTOWN, MASSACHUSETTS, ASSIGNOR TO HOOD RUBBER COMPANY, OF WATERTOWN, MASSACHUSETTS, A CORPORATION OF MASSACHUSETTS.

MULTIPLE FASTENER.

Application filed July 2, 1925. Serial No. 41,188.

To all whom it may concern:

Be it known that I, JOSEPH E. PERRAULT, a citizen of the United States, and a resident of Watertown, in the county of Middlesex and State of Massachusetts, have invented certain new and useful Improvements in Multiple Fasteners, of which the following is a specification.

The said invention relates to fasteners of the type in which two series of cooperating clasp members are successively engaged or released by the progressive movement of a slide member.

The invention thus aims to provide a fastener of this type which will be of extreme flexibility, which may be easily operated, and in which separation of the interengaged parts will be effectively prevented, irrespective of the amount of flexing of the seam or closure.

The invention further aims to provide a construction which may be economically manufactured and assembled.

With these and other objects in view the invention includes the novel features of construction and arrangement and combination of parts hereinafter described and defined by the appended claims.

In order that the invention may be better understood, reference is made to the accompanying drawings, in which:

Figure 1 is a plan view showing a pair of stringers with my improved fasteners applied thereto.

Fig. 1^a is a section through the slider on line 1^a-1^a of Fig. 1.

Fig. 2 is a section on line 2-2 of Fig. 1.

Fig. 3 is a perspective view of one of the male members before application to the stringer.

Fig. 4 is a side elevation of the same in place upon a stringer (shown in section), the dotted lines indicating the clamped position.

Fig. 5 is a plan view of the male element.

Fig. 6 is a view similar to Fig. 3, but showing one of the female elements.

Fig. 7 is a view similar to Fig. 4, but showing the female element.

Fig. 8 is a plan view of the same.

Figs. 9, 10 and 11 are detail views showing modifications of male elements.

Figs. 12, 13 and 14 are similar views of modified forms of the female elements.

Fig. 15 is a perspective view of a bottom connecting and stop member.

Fig. 16 is a section on line 16-16 of Fig. 1.

Fig. 17 is a perspective view of a permanent top stop member.

Fig. 18 is a section on line 18-18 of Fig. 1.

Fig. 19 is a perspective view of a modified form of supplemental stop member.

Fig. 20 is a view of a modified form of arrow head for the male member.

Referring by reference characters to this drawing, and first to Fig. 1 thereof, the numerals 1, 1, etc., designate the male members, and 2, 2, etc., the female elements, which are shown in said figure in place upon the stringers 3 hereinafter more fully described.

Each male element as shown in detail in Figs. 3, 4 and 5, comprises a body and an arrow-shaped head 1^b, having relatively sharply inclined front faces 1^c and rear reversely inclined shoulders 1^d, the front faces forming the leading-in parts and the rear shoulders the retaining parts. The body portion is provided with a transverse substantially cylindrical passage therethrough, indicated at 1^e, adapted to receive the bead of the stringer, the rear face being provided with an open slot leading to said cylindrical recess, as indicated at 1^f.

The member is made of a malleable metal with the edges of the stringer receiving slot 1^f separated in the manufacture, and after a plurality of these have been threaded upon the stringer, as shown in Fig. 7, the member is subjected to compression to force the bifurcated body portion into cooperating engagement with the stringer, as shown in dotted lines in Fig. 8. This stringer preferably comprises a strip of flexible material 3^a conveniently of woven fabric coated with an adhesive, such

for example as rubberized stock where the fastener strip is incorporated in a shoe upper, such strip of material being folded

90

95

90

around a bead forming core 3^b of flexible but relatively inextensible material, such for example as a cord.

The stringer for shoe construction may 5 be conveniently made of bias cut stock to enable it to be properly incorporated in the shoe and to impart flexibility, and further flexibility may be secured by providing substantially V-shaped notches in the edges of 10 the fabric, as indicated at 3^b.

When a series of these elements are threaded upon the stringer in properly spaced relation, as shown in Fig. 1, and subjected to compression, they not only 15 tightly clamp the stringer, but imbed themselves therein, such imbedding action being indicated by the dotted lines in Fig. 7, in which view the dotting is exaggerated to show the imbedding action, the construction and 20 application being such that the imbedding takes place mostly in the bead to avoid cutting the fabric. This imbedding anchors the elements in position along the stringers.

Before the element is compressed upon the 25 stringer, its rear faces 1^b lie in one and the same plane so that after it is compressed upon the stringer, said rear faces are inclined inwardly, or present a sort of dovetailed effect, as shown by the dotted lines, 30 Fig. 4, to cooperate with the corresponding inclined faces 4^b of the slide 4 (Fig. 2), as I have found that this arrangement produces a better guiding action between the fastener members and the slider.

35 Each female member 2 comprises an approximately rectangular block or member having its rear portion constructed similar to the rear end of the male member for application to, and clamping upon the 40 stringer, as will be obvious from the drawings. The forward end of the female member is made of approximately wedge shape, or in other words, is provided with sharply inclined leading-in edges 2^a, and is recessed 45 adjacent its forward end to receive the corresponding projecting portion of the cooperating arrow head of the male member. For convenience in manufacture, the recess is preferably formed in the shape of an 50 opening 2^b extending clear through the member. The recesses extend into the inclined portions and with the male and female members properly spaced it will be apparent from Fig. 1 that the arrow head of 55 each male member engages the eyes of each of the adjacent or juxtaposed female members, and with the stringers parallel, as shown at the left of Fig. 1, it will be observed that the rear shoulders of the arrow 60 heads engage behind the forward or outer walls of the recesses and securely lock the parts together.

65 By reason of the wedge shape of both the arrow heads and the ends of the female members, the parts are readily brought to-

gether by the action of the slider, as indicated by the dotted lines on the right of Fig. 1, and separation is likewise facilitated by the inclusion of the rear shoulders of the arrow heads.

70 The slider comprises a sheet metal casing having internal diverging guides or channels which engage the male and female members respectively, so that when the slide 4 is moved to the right (by means such as pivoted handle member 29, Fig. 1), the male and female members are brought successively into interlocking engagement, whereas when the slider is moved to the left, Fig. 1, disengagement is effected.

75 The top and bottom walls 4^b of the slider are preferably parallel to each other, as shown in Fig. 2, and the outer face portions 1^x and 2^x of the male and female members are parallel to each other and fit the internal faces of the slider walls 4^b with an easy sliding fit, while the faces 1^y and 2^y are machined towards each other, which facilitates the entrance of the members into the slider.

80 The two stringers may be connected at the closed end (left, Fig. 1), which would correspond to the bottom of the shoe opening where the fastener is used in connection with a shoe upper, by any suitable means, preferably a pronged sheet metal member 5, Fig. 15, having prongs 5^a adapted to penetrate the fabric adjacent the beaded edge of the stringer and be clinched over the under side of the bead, which connecting member would serve as a stop to limit the movement 85 of the slide in that direction. The connecting member is preferably stamped up into a trough shape, as shown in Fig. 15.

90 Limit of movement in the other direction may be secured by cup shaped sheet metal stop members 6 having riveted prongs 6^a (Fig. 17) adapted to pass through the stringer and be clamped over on the under side thereof, as shown in Fig. 17.

95 Supplemental insertible and adjustable stop means may be provided in the shape of a member 7 insertible in the eyes of two adjacent female members whereby a stop member may be placed between any two female members by flexing the stringer to spread its wedge-shaped ends sufficiently apart. The stop member indicated at 7, Fig. 1, is provided as shown with two cylindrical ends fitting the respective recesses of the adjacent female members and with an intermediate flange 7^a, which holds the stop member spaced against displacement when the parts are in normal position. As the slide moves to the right it will readily be seen that when the last male member aligns with the flange 7^a it will be prevented thereby from entering the space between the two female members and this will check the movement of the slider to the right. Instead of having 100 the flange 7^a centrally arranged of the stop

member, it may be arranged at one end, as indicated at 7^b, Fig. 19, so that the balance of the body of the stop member will be held entirely within the recess of one of the female members. Then when the wearer of shoes equipped with stops 6 wishes to limit the outward movement (to the right, Fig. 1) before the stops 6 are reached, according to the style of "flapping" in vogue, it is only necessary to insert a supplemental stop anywhere desired in the train by swinging one of the fastener members aside. Of course the stop members 6 might be omitted if desired and a supplemental stop member 7 relied on for the stopping action.

While I have shown in the figures above described the inclined or wedge-shaped surfaces of the male and female members as substantially plane, it will be obvious that these surfaces may be modified in various respects. For example, the male member may have its outer faces formed on convex curves, as indicated at 1¹, Fig. 9, and the female member may have correspondingly curved faces, as indicated at 2¹, Fig. 12. Furthermore the said faces of the male member could be made on a convex curve in a direction at right angles to that shown in Fig. 9, as indicated at 1² in Fig. 10, and the female member provided with corresponding concaved faces, as indicated at 2² in Fig. 13.

While it is desirable in many types of articles that the fasteners be relatively small and a large number of them provided for a given length of closure opening, I have found that my construction is such that the male and female fasteners respectively may be made very wide, as indicated at 1³ and 2³, Figs. 11 and 14 respectively, without detracting from the appearance of the article or interfering with the ease of operation thereof or the security of the fastening, this construction very much reducing the cost.

It will be noticed that the lead-in faces 1^c of the male members are at an acute angle to each other or relatively sharply inclined, while the retaining faces are at an obtuse angle to each other or less sharply inclined. This in connection with the wedge shaped and recessed female members makes a very smooth working multiple fastener.

If desired, the edges of the arrow head of the male member may be beveled, as shown in Fig. 20.

Having thus described my invention, what I claim is:

1. A fastener comprising clasp members arranged in cooperating series, the members of one series being provided with recesses and inclined guides leading thereto, and the members of the other series having converging sides for slidably engaging said guides and having angularly disposed shoulders engageable in the recesses of adjacent members of the first named series.

2. A fastener comprising clasp members arranged in cooperating series, the members of one series being provided with recesses and diverging side faces forming inclined guides leading to said recesses, and the members of the other series being provided with tapered heads to slidably cooperate with said guide faces, and abrupt shoulders for engaging the walls of the recesses. 70

3. A fastener comprising clasp members arranged in cooperating series, the members of one series being provided with recesses and diverging side faces forming inclined guides leading to said recesses, and the members of the other series being provided with wedge-shaped heads to slidably engage said guide faces, and having rear shoulders which meet the faces of the wedge-shaped heads at relatively sharp angles. 75

4. A fastener comprising clasp members arranged in cooperating series, the members of one series being provided with recesses and inclined guides leading thereto, and the members of the other series having converging sides for slidably engaging said guides and having angularly disposed shoulders engageable in the recesses of adjacent members of the first named series, said members of the second series having flat top and bottom faces. 80

5. A fastener comprising clasp members arranged in cooperating series, each of said fasteners having the rear portion of its top and bottom faces parallel and the front portions of said faces inclined towards each other, in combination with a slide member having parallel faces cooperating with the parallel faces of said members. 85

6. The combination with a multiple fastener comprising fabric stringers having beaded edges, attached clasp members, and a cooperating slider, of a stop member having prongs penetrating the fabric and bent over to embrace the bead. 90

7. In a multiple fastener a pair of fabric stringers having beaded edges and cooperating clasp members, and a stop member comprising a hollow sheet metal body having fabric penetrating and bead engaging prongs projecting from the edges thereof. 105

8. In a multiple fastener a pair of fabric stringers having beaded edges and cooperating clasp members, a slide cooperating with said fasteners, a permanent stop carried by one of said stringers for limiting the closing movement of the slide, and an attachable and detachable stop for arresting the movement of the slide before reaching said permanent stop. 115

9. A fastener comprising clasp members arranged in adjacent cooperating series, the members of one series being provided with eyes, and the members of the other series being provided with substantially arrow-shaped heads, each of which is engageable 125

in the eyes of adjacent members of the first named series, a slide cooperating with said members, and a stop member insertible in the eyes of a pair of adjacent members with means for retaining it therein.

10. A fastener comprising clasp members arranged in adjacent cooperating series, the members of one series being provided with eyes, and the members of the other series being provided with substantially arrow-shaped heads, each of which is engage-

able in the eyes of adjacent members of the first named series, a slide cooperating with said members, and a stop member insertible in the eyes of a pair of adjacent members, said stop member having an abutment to cooperate with the adjacent faces of the fastener members to prevent displacement of the stop member.

In testimony whereof I affix my signature.

JOSEPH E. PERRAULT.
